FURNACE

William Svejkovsky, Oklahoma City, Okla.

Application January 15, 1937, Serial No. 120,815

3 Claims. (Cl. 126—116)

The invention relates to furnaces and particularly to the pipeless type, and has for its object to provide a furnace of this character wherein the products of combustion pass to the flue through a plurality of drums in an upwardly and downwardly direction, thereby wiping the walls of the drum interiors so that the heat units therein will be taken up and radiated and absorbed by the falling of cold air, which is heated so it will 10 pass upwardly and be discharged into a room.

A further object is to position all of the drums in spaced relation but adjacent each other whereby air passages for the heated air is formed between the drums as well as to the outer side thereof, thereby obtaining maximum radiating surface from all the drums.

A further object is to provide spaced walls around the drums in spaced relation thereto and between the down-flowing cold air and up-flowing heated air and forming an insulating chamber whereby the up-flowing air will not affect the down-flowing cold air.

With the above and other objects in view, the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:

Figure 1 is a perspective view of the furnace showing parts of the various casings broken away and in section to better show the structure.

Figure 2 is a top plan view of the furnace.

Referring to the drawing the numeral 1 designates the rectangular shaped casing of the furnace which houses all of its parts. Disposed centrally within the rectangular casing 1 is a rectangular shaped main drum 2, in the lower end of which is disposed a conventional form of gas burner unit 3. It is to be understood however that any kind of a burner unit may be used. The upper end of the main drum 2 is provided with a removable closure 4, which may be removed so the operator may see the flames from the burners 3, or the pilot burner 5, during an adjusting operation. Gas is applied to the burners 3 through the gas supply pipe 6, and the pilot supply pipe 7 in the usual manner, and these pipe lines are provided with control valves 8 and 9 having upwardly extending valve stems 10, terminating adjacent the floor 11 of a room where they may be easily operated by a conventional form of key for regulating the flow of gas

to the burners. After the adjusting operation the closure 4 is closed. It will be noted that the main drum 2 is rectangular shaped, thereby providing a plurality of flat walls 12.

Surrounding the main drum 2 is a plurality of auxiliary drums 13, which are triangularly shaped in horizontal cross section and have their inner walls 14 in parallel relation to the walls 12 of the main drum 2 and in spaced relation thereto, thereby forming passages through which the up-flowing air, to be heated will pass and be heated from both sides of the column of up-flowing air. The heat from the burners 3 passes upwardly through the main drum 2 to the upper end thereof and thence outwardly through the branch 16 pipes 15 which connect the upper ends of the auxiliary drums to the main drum.

The products of combustion and the heat then pass downwardly through the triangularly shaped auxiliary drums 13 into engagement with the baffle plates 16. Baffle plates 16 are shaped whereby the products of combustion, in passing each baffle plate, are forced outwardly around the edges 17 of the plates and into engagement with the outer walls of the drums, thereby insuring a wiping of the walls of the drums by the products of combustion and the radiation of the heat units to the column of the air being heated as it passes upwardly in engagement with all the outer walls of the main and auxiliary drums within the insulation casing 18. The insulating casing 18 surrounds the auxiliary drums in spaced relation thereto and has a dead air space 19 therein for preventing loss of heat units to the downwardly flowing cold air passing through the cold air chamber 20 within the casing 1. The cold air passes downwardly in the direction of the arrows a and upwardly around the lower edge of the insulation casing 18, and is heated as it passes upwardly, wiping the outer walls of the drums, and is discharged into the room. It is to be understood a conventional form of grating may be placed over the furnace in the usual manner. To prevent the too rapid flow of the products of combustion to the chimney flue pipe 21 through the discharge pipe 22 and downwardly draft preventer 23, a triangular shaped restricting plate 24 is provided in each of the auxiliary drums adjacent the flue pipe 2 and above the pipe 22, and provided with a central discharge opening 25. It will be seen that the plates 24 will have a choking effect or back pressure effect which will prevent the too rapid passage of the heat and products of combustion to the flue, thereby allowing the absorption of the heat units to a maximum 55

degree by the in-rushing cold air as it is re-heated, consequently reducing flue heat loss to a minimum.

- The lower ends of adjacent auxiliary drums 13 are connected together by pipes 26, which discharge into the drums 13 adjacent the flue pipe 21 below the choke plates 24, thereby allowing the equalization of the choking effect through the drums.
- 10 The down draft preventer 23 is provided on the flue pipe 21 for preventing a down draft from extinguishing the pilot or burners or having an effect upon their efficiency. It consists of a rectangular shaped casing as shown in Figure 1, which has its lower end open and a partition 27 extending to the bottom of the casing and spaced from the upper end of the chamber therein. The products of combustion pass through the pipe 22, thence downwardly and over the partition 17 in the direction of the arrows b to the chimney flue pipe 21. If there is a down draft, the down draft will engage the partition 27 and will pass through the open bottom of the casing and be discharged from the device into the basement or room in which the furnace is placed.

By forming the various drums rectangular and triangular shaped as shown in Figure 2, it will be seen that a rectangular shaped assembly is obtained within the insulating casing 18 which places all of the walls in parallel relation and spaced so that large radiating surface is obtained for the heat units and the heated air rises in relatively narrow columns of uniform thickness thereby insuring a uniform heating of the columns of up-moving air.

From the above it will be seen that a hot air furnace is provided, which is simple in construction, and one wherein a maximum heating surface is obtained, and the drums provided with

baffle means which will positively force and deflect the products of combustion outwardly against the inner surfaces of the walls of the auxiliary drums.

The invention have been set forth what is 5 claimed as new and useful is:

1. A furnace comprising a rectangularly shaped main casing, an auxiliary casing within the main casing in spaced relation thereto and rectangularly shaped, the auxiliary casing having 10 its corners in registry with the corners of the main casing, insulating means carried by the auxiliary casing, a rectangularly shaped main drum within the auxiliary casing and having its corners substantially ninety degrees from the corners of the auxiliary casing, triangularly shaped auxiliary drums in the similarly shaped chambers formed by the main drum and corners of the auxiliary casing, a heating element in the main drum, flue connections between the main 20 and auxiliary drums for passage of gases therethrough, the adjacent faces of all of the drums being in spaced relation to each other and in spaced relation to the auxiliary casing thereby forming flat air passages for the passage of heat- 25 ed air.

2. A device as set forth in claim 1 wherein the flue connections between the drums comprise radially extending members from the adjacent flat sides of the drums and members extending 30 across the corners of the main drum and connecting the triangularly shaped drums.

3. A device as set forth in claim 1 wherein the adjacent sides of the main and auxiliary drums are flat and equidistant from each other and the 35 corner angles of the auxiliary drums and outer sides thereof parallel to the adjacent portions of the corners of the auxiliary casing.
